CABINET FOR TOOTHBRUSHES

Charles F. Tomson and Walter I. Fritz,
Albert Lea, Minn.

Application February 1, 1932, Serial No. 590,053

4 Claims. (Cl. 206—15.1)

This invention relates to a device for holding and protecting tooth brushes. It is now the common practice to keep tooth brushes in the bathroom either on a shelf or disposed in an open 5 rack or other open container. It is desirable to have the tooth brushes protected from dust and dirt, and it is important at the same time that they be disposed in a container in which they can readily dry out. It is also desirable to have 10 the brushes in an antiseptic or disinfecting atmosphere.

It is an object of this invention, therefore, to provide a tooth brush protecting device comprising a cabinet having an open front closed by a 15 door tending to swing to closed position, said cabinet having a bottom portion containing a disinfecting means together with means therein for holding a plurality of tooth brushes with the bristle portions closely adjacent said disinfecting means, means also being provided for permitting a circulation of air through the said cabinet.

It is a further object of the invention to provide a tooth brush protecting device having in 25 combination a cabinet having a bottom portion of rectangular form in horizontal and vertical cross section and having a vertical rear wall and side walls extending upwardly from the ends of said portion forming an offset with said end walls, 30 whereby said cabinet has an open front, a door hinged on a horizontal axis at the top of the cabinet and having front and side portions adapted to tightly close said cabinet when shut, with the front portion of the door alining with the 35 front of said bottom portion when the door is closed, said bottom portion having one or more openings therethrough and said side walls having one or more openings therethrough adjacent their upper ends, said bottom portion having a disinfecting means in its bottom and means on said rear wall for holding a plurality of brushes with the bristle portions thereof depending into said bottom portion closely adjacent said disinfecting means.

45 It is still another object of the invention to provide a tooth brush protecting device comprising a cabinet having an open front portion, a door for tightly closing said cabinet, a disinfecting means in the bottom of said cabinet, means for holding a plurality of tooth brushes with the 50 bristle portions thereof closely adjacent said disinfecting means, together with means for permitting a circulation of air through said cabinet.

These and other objects and advantages of the 55 invention will be fully set forth in the following

description made in connection with the accompanying drawing, in which like reference characters refer to similar parts throughout the several views and in which:—

Fig. 1 is a view in front elevation of the device, 60 certain parts being broken away and others shown in vertical section;

Fig. 2 is a view in side elevation of the device, showing the door partly open;

Fig. 3 is a horizontal section taken on line 3—3 65 of Fig. 1; and

Fig. 4 is a partial plan view of a box and cover used with the device.

Referring to the drawing, a device is shown comprising a cabinet 5 which has a trough-like 70 portion 5a at its bottom, of rectangular shape in horizontal and vertical cross section, and having a bottom, front and rear side walls and end walls. The rear side of portion 5a extends upwardly to form the rear wall 5b of the cabinet and the 75 end walls of the portion 5a extend vertically to form the sides or ends 5c of the cabinet 5. The portions 5c taper somewhat toward their upper ends and are of less width at their lower ends than the width of portion 5a, thus forming a 80 horizontal ledge or offset 5d. The upper ends of portions 5c are connected by the top wall 5e. The rear wall 5b has a plurality of small holes 5h therethrough adapted to receive screws for attaching the cabinet to a wall. A door 6 is provided, having a flat front portion and side portions 6a tapering toward their upper ends, and when the door 6 is closed, the side portions 6a overlap the sides 5c and extend somewhat below the edge 5d, the flat front portion of the door 90 substantially alining with the front of portion 5a. The front portion of the door has a projecting and slightly outturned lip 6b at its bottom adapted to be engaged for opening said door. A hinge 7 is secured to the inner side of the door 6 and 95 the inner side of the top 5e, having a pintle, the axis of which is substantially in line with the front edge of the top portion 5e. Door 6 thus swings outwardly and upwardly and tends to move to closed position by gravity. The front 100 wall of portion 5a has one or more openings 5f therethrough and the side portions 5c have openings 5g adjacent their upper ends. Openings 5f and 5g are preferably covered with fine wire screen 8. The portion 5a has disposed in the 105 bottom thereof a rectangular box or pan 9, the end walls of which have projections 9a extending upwardly and inwardly therefrom. A plate 10 having a multiplicity of holes 10a therethrough forms a cover for the box or pan 9, and slides in 110

between the end portions 9a. Pan 9 is adapted to contain some absorbent material 11 which will be saturated with formaldehyde solution or some other antiseptic or disinfecting solution. A plate 12 extends across the cabinet horizontally between the side walls 5c having a vertical flange 12a secured to the inside of the rear wall 5b in any suitable manner as by soldering or welding. Said plate has formed therein a plurality of semi-circular openings 12b and slots with outwardly diverging sides 12c extend from said openings forwardly to the front edge of said plate.

In operation the plate 12 is adapted to receive the handles 14a of the tooth brushes 14. The handles 14a are usually of less thickness than width and can be inserted through the slots leading to the openings 12b at their small portions, or they can be turned edgewise and passed through said slots. In the latter case the handles will then be turned with their wide dimension extending longitudinally of the plate 12. The handles will then be retained in the plate 12 and in the openings 12b therein and the bristle portions 14c of the brush will be disposed in the lower portion of the cabinet and closely adjacent the plate 10, in some instances resting on said plate. The brushes preferably will be turned with the bristles directed forwardly. As stated, a disinfecting solution will be placed in the pan 9 and the fumes or vapors from this can pass upward through the holes 10a into the cabinet. Pan 9 is readily removable and can be lifted by the portions 9a. The disinfecting solution can be placed therein while the pan is removed. The circulation through the cabinet will be permitted by the holes 5f and 5g and the air will pass into the holes 5f upwardly in the cabinet and out through the holes 5g. The fumes from the disinfecting solution will thus be effectively carried to and through the bristles 14c of the brushes 14. The brushes will be dried by the circulation and will at the same time be kept in a clean and sanitary condition. By disposing the bristles downwardly, water will not drain down on the handles. The screen 8 will prevent the entrance of flies and other insects into the cabinet. The brushes are thus kept in desirable condition in a tightly closed cabinet and are completely protected against dust and dirt. The cabinet will be made of polished metal or the same can be coated with nicely appearing colors made to match the finish of the bath room.

From the above description it is seen that applicant has provided a simple and efficient tooth brush holding and protecting device in which the brushes are kept in a clean and sanitary condition. The device is easily made and can be readily installed in the desired position. It not only has a high degree of utility, but has an ornamental appearance, adding to the appearance of the bath room or other place in which it is disposed. The device has been amply demonstrated in actual practice and found to be very successful and efficient.

It will, of course, be understood that various changes may be made in the form, details, arrangement and proportions of the parts, without departing from the scope of applicants' invention, which generally stated, consists in a device capable of carrying out the objects above set forth, in the parts and combinations of parts disclosed and defined in the appended claims.

What is claimed is:—

1. A tooth brush protecting device having in

combination, a cabinet having a lower portion of rectangular shape in horizontal and vertical cross section, a rear wall rising vertically from the rear of said portion, side walls of less width than the ends of said portion extending vertically and tapering upwardly, the same forming an offset with the end walls of said portion, a door hinged on an axis adjacent the top of said cabinet having upwardly tapering sides and tending to swing to closed position, the front of said door alining with the front side of said portion when closed, a disinfecting means in the bottom of said portion, and means above said portion for holding a plurality of tooth brushes with the bristle portions disposed downwardly and closely adjacent said disinfecting means. 80

85

90

2. A tooth brush protecting device having in combination, a cabinet having a lower trough-like portion and tapering upwardly in depth to its top, said cabinet being open at its front above said trough-like portion, a door hinged at its top adapted to close said front, a removable pan in the bottom of said trough-like portion, a reticulate cover for said removable pan, means adjacent the midportion of said cabinet for holding a plurality of brushes in said cabinet with their bristle portions disposed downwardly and closely adjacent said cover, said cabinet having openings adjacent said pan and also adjacent its top for the circulation of air upward in said cabinet. 95

100

3. A toothbrush protecting device having in combination, a cabinet having a lower portion of rectangular shape in horizontal and vertical cross section, said portion forming a trough, a rear wall rising vertically from the rear of said portion, side walls of less width than the ends of said portion extending vertically and tapering upwardly, the same forming a horizontal offset with the end walls of said portion, a door hinged on an axis extending horizontally adjacent the front of said cabinet having upwardly tapering sides and tending to swing to closed position, the front of said door alining with the front side of said portion when closed, a pan of rectangular form fitting in said trough, a disinfecting substance disposed in said pan, said pan being disposed well below said offset, a perforated cover for said pan, holding means for a plurality of toothbrushes disposed substantially midway vertically of said rear wall for holding toothbrushes 110 with the bristle portions disposed downwardly and closely adjacent said perforated cover, said cabinet having vent openings adjacent said perforated cover and also adjacent the top thereof causing a circulation of air vertically through 115 said cabinet and through said bristle portions. 120

4. A tooth brush protecting device having in combination, a cabinet having a lower trough-like portion, said cabinet having an open front above said trough-like portion, a door hinged to 135 said cabinet and adapted to close said front to form a substantially closed cabinet, a pan in the bottom of said trough-like portion, a reticulate cover for said pan, means intermediate said pan and the top of said cabinet for suspending a plurality of tooth brushes with the bristle portions thereof disposed downwardly and adjacent said cover, said cabinet having means for causing a circulation of air adjacent said cover and bristle portions and through the upper portion of said 140 cabinet. 125
